UNITED STATES PATENT OFFICE.

WALTER E. PIPER, OF MELROSE, MASSACHUSETTS, ASSIGNOR TO BOSTON RUBBER SHOE COMPANY, A CORPORATION OF MASSACHUSETTS.

DESIGN FOR THE SOLE OF A RUBBER OVERSHOE OR SIMILAR ARTICLE.

55,529.

Specification for Design. Patented June 22, 1920.

Application filed August 7, 1915. Serial No. 44,332. Term of patent 14 years.

To all whom it may concern:

Be it known that I, WALTER E. PIPER, a citizen of the United States, residing at Melrose, county of Middlesex, and State of Massachusetts, have invented a new, original, and ornamental Design for the Sole of a Rubber Overshoe or Similar Article, of which the following is a specification, reference being had to the accompanying drawing, forming part thereof, wherein—

Figure 1 is a side elevation of an overshoe showing my new design, the design being confined to the sole portion thereof.

Fig. 2 is a bottom plan view of the same.

I claim:

The ornamental design for the sole of a rubber overshoe or similar article.
